UNITED STATES PATENT OFFICE

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY

STEAM BOILER

Application filed October 29, 1921, Serial No. 511,357. Renewed November 21, 1928.

My invention relates to water-tube boilers, particularly of the type in which upper and lower horizontal drums are connected by water tubes, and in which the hot gases flow in a generally horizontal direction.

My invention will be understood by reference to the accompanying drawings, in which Fig. 1 shows a side elevation, with some of the boiler setting broken away, of an illustrative form of boiler embodying my invention; Fig. 2 is a vertical section on the line 2—2 of Fig. 1; Fig. 3 is a plan view of Fig. 1, with some of the parts broken away; Fig. 4 is a development of a portion of a drum sheet of the arrangement shown in Fig. 1; Fig. 5 is a more or less diagrammatic representation of some of the tubes showing the relation of the rows and of the tubes within the rows; Fig. 6 is a side elevation, partly in section, of still another embodiment of my invention; Fig. 7 is a plan view of Fig. 6 with some of the parts broken away or removed for a better understanding of the disclosure; Fig. 8 is a vertical section of Fig. 6 on the line 8—8; Fig. 9 is a development of a portion of the drum sheet of the arrangement shown in Fig. 6; Fig. 9^a is a cross-section showing the staggered arrangement of the tubes in the form of boiler shown in Figs. 6, 7 and 8; Figs. 10, 11 and 12 are enlarged sections respectively on the lines X—X, Y—Y and Z—Z of Fig. 9; Fig. 13 is an enlargement of a portion of Fig. 9; Fig. 14 is a more or less diagrammatic showing of the tube arrangement of Fig. 6 and represents a section taken parallel to a row of tubes through a portion of the lower drum; Fig. 15 is an enlarged section of a portion of a drum taken parallel to a row of tubes; Fig. 16 is a section at right-angles to the axis of the drum; Fig. 17 is a view of part of Fig. 16 looking from the left of that figure; Fig. 18 is a side view of a portion of Fig. 15; Fig. 19 is an enlarged section of the lower drum of the arrangement shown in Fig. 6; Fig. 20 is a side elevation, also enlarged, of the same drum and some of the tubes; Fig. 21 is a section on line 21—21 of Fig. 20, and Fig. 22 is a plan view of Fig. 20.

Like reference characters refer to like parts in the several views.

Referring now to the arrangement shown in Figs. 1, 2 and 3, 10 is an upper steam and water drum and 11 a lower water drum, which drums are horizontal and one above the other, with the upper drum 10 projecting beyond the end of the lower drum 11. Rows of inclined water tubes 12 connect these drums in a manner to be described more specifically hereinafter and beneath the row of tubes at the left of Fig. 1 is located a furnace chamber 13 having any suitable means for burning any desired kind of fuel.

Side walls 14, 15 provide a flue from the furnace chamber 13 to conduct the gases therefrom toward the right of Fig. 1, such gases ultimately passing out of the gas outlet 16.

Within the flue formed by these side walls are arranged the tubes 12 in rows extending across the flue, such arrangement being best shown in Fig. 2. Preferably, these tubes are divided in groups by baffles, the baffle 17, which is the one nearest the furnace chamber 13, being located, in the illustrative form, behind two rows of the tubes 12 and extending from the lower drum 11 up toward the upper drum 10, with a sufficient space between that drum and the top of the baffle to provide a gas passage. Similarly, a baffle 18 extends downward from the upper drum 10, and another baffle 19 extends up from the lower drum 11. The rear of the setting is closed by the rear wall 20.

Some of the rows of tubes are spaced apart, as best shown in Fig. 1, to provide a superheater chamber which, preferably, is located between the baffles 17 and 18, and in this superheater chamber is located a U-tube superheater 21 to the inlet header of which the steam from the drum 10 is conducted by the pipe 22 and from which the steam is taken through the outlet pipe 23.

It will be seen that in the form of boiler just described, the entire space between the front and rearmost rows of tubes is filled with rows of tubes which are parallel the greater portion of their length and through which the gases pass by flowing substantially parallel with the greater portion of each tube, the gases passing from the chamber 13

- over the baffle 17, under the baffle 18 and over the baffle 19 to the gas exit 16. By having the tubes inclined over the furnace chamber 13, such tubes form a roof for the furnace, and at the same time, by making the gas passage at the upper end of the baffle 17, a combustion chamber is provided in which the gases will be mixed and burned before entering the tubes. The two rows of tubes 5 in front of the baffle 17 will protect the latter from the direct heat of the furnace and will also absorb the radiant heat of the fire.
- 10 The tubes 12 are expanded into the drums 10 and 11 in the usual manner, and it is desirable that the tubes shall enter each drum 15 radially. This is accomplished by an arrangement of tubes which will appear as shown in Fig. 2 when viewed from the end of the boiler.
- 20 In order that the tubes may enter the drums radially and that at the same time, the greater portions of such tubes may be inclined as shown in Fig. 1, I have provided a method of bending and inserting the tubes, so that 25 each tube will have only two bends. This, however, will involve a peculiar arrangement of the holes in the drum, such holes falling in curves which are illustrated in Fig. 4, the relation between the upper and lower 30 ends of the tubes being also shown in Fig. 1. The bend at either end is determined by certain fixed conditions in each tube. As will be seen by an inspection of Figs. 1 and 2, in each tube there will be a straight portion 35 which is parallel to the straight portions of all of the other tubes, and this straight portion will have a relation to the axes of the two drums in accordance with the position of the tube relative to the vertical axis of the boiler. Beginning at the tubes nearest 40 this vertical axis, it will be obvious that the end of the tube which enters the drum must lie in a nearly vertical line radial to the drum, and that, therefore, the curve between 45 the tube end and the inclined straight portion of the tube may be an arc of a circle to which these two straight portions will be tangent, the bends at the opposite ends of the tubes being on opposite sides of the plane 50 of the row in which the tube is located. Similarly, the next tube must enter the drum on a radial line, but this radial line will be at an angle to the vertical, and the curve 55 which connects this radial line with the center line of the inclined straight portion of the tube may also be an arc of a circle to which the center lines of the inclined straight portion and of the end of the tube will be tangent. The holes for the tubes in the drums should 60 be spaced along the axis of the drum as well as around the drum. In other words, the intersections of the normals of the tube holes in the drum will be spaced along the axis of the drum. In such an arrangement, no two 65 of the tubes from the center to the outside

of a row will have the same curvature at their ends, but each tube will have only two bends, with the bend at one end out of the plane of the bend at the other end.

In the arrangement shown in Figs. 1 and 70 2, it may be desirable in order to provide minimum space conditions and reasonable ligaments between the tube holes in the drum sheet, to have the inner tubes staggered while the outer tubes are parallel. Such an arrangement is shown in Fig. 5, in which the 75 four outer tubes at either side in each row are arranged one behind the other, while the remaining tubes are staggered. Such an arrangement of tubes, when applied to a construction in which each tube is to have only 80 two bends, will produce a drum sheet, the development of which will be such as is illustrated in Fig. 4, the center line for each row being as indicated for one of the rows by 85 the line V—V in Fig. 4.

In Figs. 6 to 8, inclusive, I have illustrated a form of boiler in which the tubes may be bent in one plane only and yet be inclined 90 forwardly and will also enter the drum normal to the surface of the drum. In the boiler shown in Figs. 6 and 8, the parts are substantially the same as those shown in Fig. 1, and are correspondingly numbered, and a repeated detail description thereof will be 95 unnecessary. The form of boiler shown in Fig. 6 is provided with an underfeed stoker instead of the hand-fired grates shown in Fig. 1.

In the arrangement shown in Fig. 6, the 100 tubes are arranged in parallel rows and each tube is bent in a single plane at each end and, in order to permit such a single bend to enter the drum normal to the surface thereof, I provide the drum with steps or bumps, the 105 construction of which will be best understood by an inspection of Figs. 10 to 13, inclusive. The angle which the axis of the end of a given tube will make with the cylindrical 110 surface of the drum is first determined, and then the portion of the shell into which the 115 end of that tube is to be entered is shaped by suitable dies, so that the portion through which the tube hole is made will lie at right-angles to this axis. It will be obvious that 120 since each tube end makes a different angle with the cylindrical surface than that made by its neighbor in the row, the angle which the plane of this face will make with the cylindrical drum surface will be different for 125 each of the tubes in a row beginning at the center and extending to the side. In Figs. 10 to 12 are shown enlarged sections of the steps 122, 132, and 142 for three adjacent tubes 121, 131 and 141 in a given row, and in Fig. 13 a plan view of these steps is shown. In this plan view, for sake of clearness, the steps are shown as if the faces and sides thereof formed a sharp angle, but in actual construction, these edges will be rounded, as 130

shown in Figs. 10 to 12, inclusive. With the staggered tube arrangement as shown at the left of Fig. 9, the development of the drum sheet will be as shown in Fig. 9, with the tube holes forming curves around the drum but spaced along the length of the drum as well as across it.

5 In Fig. 14 is shown a section of a part of the drum taken parallel to the tube row and showing the center lines of the tubes of a row and the curves at the ends of each of them.

10 In Figs. 15 to 18, inclusive, are shown sections or side views of the drum sheet as it will be bumped or stepped to receive some of the tubes, the hole 121 being formed in the step 122, the hole 131 in the step 132 and the hole 141 in the step 142, these holes receiving the ends of tubes 12, 13 and 14 indicated in Fig. 8, and the relation of these holes to the others 15 in the same row being also shown on the drum sheet development in Fig. 9.

20 In Fig. 22, a plan view of a portion of the lower drum 11, with some of the tubes of a row entering the same, is shown which will further illustrate the character of the steps 25 which are formed.

25 The boiler which I have illustrated in various embodiments is efficient and at the same time, economical to construct. By having the tubes inclined over the furnace chamber, the radiant heat is absorbed and at the same time, the difficulties arising from the maintenance of refractory roofs and arches are avoided. While, for some purposes, the 30 gases might be carried straight back horizontally to the gas outlet, I find that, by providing baffles so as to compel the gases to flow up and down along the main portions of the tubes as the gases flow horizontally, there 35 will be a more efficient passage of the heat from the gases to the tubes. By arranging all of the tubes in parallel rows, it will be obvious that all tubes in like situations will be duplicates of each other. That is to say, all 40 of the outermost tubes, for instance, in each row on one side will be alike except where the rows are staggered, in which case, the outermost tubes in each alternate row will be duplicates. Moreover, by placing all of the 45 tubes in parallel rows, all of the boiler space may be filled with tubes so as to give a compact and efficient arrangement. If a superheater is used, then a space for it may be readily provided by omitting certain of the 50 rows of tubes at a point where it is desired to place the superheater, and where high superheat is desired, such space may be provided in the first pass of the boiler, so that the 55 superheater tubes will be contacted by the hot gases after these gases have passed over a few water tubes only. Moreover, the upper and lower drums will be similar so far as the arrangement of the tube holes therein are concerned, which is an important consideration 60 in the cost of manufacture.

While the arrangements shown in Figs. 6, 7 and 8 involve the forming of steps in the drum sheet, a great advantage is derived therefrom in the fact that the tubes in this arrangement are simple in design, and, moreover, have the fewest possible number of forms of tubes for the boiler, because each tube at a given distance from the vertical axis of the boiler will be the same as the tube at the same distance from this vertical axis 75 but on the opposite side thereof.

80 While, in the various forms, I have shown the tubes as staggered, it will be obvious that this is not essential.

85 While I have described the drums as cylindrical, it will be understood that drums of other cross-sections may be used, if desired. In such case, however, the portion of the drum sheet entered by the tubes will be curved and the bends and steps which I have described will therefore also apply to such 90 constructions. In the appended claims, when I describe the drums as cylindrical, it will be understood that I include in that term any drum in which the part entered by the tubes 95 is a part of a cylinder. It will also be understood that, while I have shown the upper and lower drums as of the same length, the upper drum may be extended, if desired, until the end of the upper drum farthest from the 100 furnace is over the corresponding end of the lower drum. Such an arrangement would give a vertical rear wall instead of the inclined rear wall which I have illustrated, and will also give added steam and water space, 105 so that the steam could be taken from a point in the drum beneath which there are no water tubes.

I claim:

1. In a water-tube boiler, an upper and 105 a lower cylindrical drum, with their axes horizontal and parallel, a furnace, a flue arranged to conduct the hot gases from the furnace between and longitudinally of the drums, a plurality of water tubes in the 110 path of the gases and connecting the upper and lower drums, the tubes being arranged in rows extending across the flue, with the greater portion of each of the tubes in each row in a plane perpendicular to the plane of 115 the axes of the drums and inclined toward the furnace end of the flue, the distance between the outer tubes in each row being greater than the diameter of one of said drums, the axis of each end of each tube 120 being normal to that portion of the shell of the drum which the end enters and each tube having no more than two bends.

2. In a water-tube boiler, an upper and a lower cylindrical drum, with their axes horizontal and parallel, a furnace, a flue arranged to conduct the hot gases from the furnace between and longitudinally of the drums, a plurality of water tubes in the 125 path of the gases and connecting the upper

and lower drums, the greater portion of each tube being inclined to the horizontal in a direction parallel to the plane of the axes of the drums, such greater portion of some of said tubes being outside the projected area of at least one of said drums, and the axis of each end of each tube being normal to that portion of the shell of the drum which the end enters and each tube having no more than two bends.

3. In a water-tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the greater portion of each tube being inclined to the horizontal in a direction parallel to the plane of the axes of the drums, such greater portion of some of said tubes being outside the projected area of at least one of said drums, and each tube being bent in a single plane, the portion of the shell of the drum which the end of a tube enters comprising a step normal to the axis of the end of the tube.

4. In a water-tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the greater portion of each tube being inclined to the horizontal in a direction parallel to the plane of the axes of the drums, such greater portion of some of said tubes being outside the projected area of at least one of said drums, and each tube having no more than two bends and the bends being in a single plane, the portion of the shell of the drum which the end of a tube enters comprising a step normal to the axis of the end of the tube.

5. In a water-tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending across the flue, with the greater portion of each of the tubes in each row in a plane perpendicular to the plane of the axes of the drums and inclined toward the furnace end of the flue, the distance between the outer tubes in each row being greater than the diameter of one of said drums, the tubes being bent between the ends and the inclined portion and all of the bends in each tube being in a single plane, the portion of the shell entered by the ends

of the tubes having steps normal to the axes of the ends of the tubes.

6. In a water-tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending across the flue, with the greater portion of each of the tubes in each row in a plane perpendicular to the plane of the axes of the drums and inclined toward the furnace end of the flue, the distance between the outer tubes in each row being greater than the diameter of one of said drums, the planes of the several rows being parallel, the tubes being bent between the ends and the inclined portions and all of the bends in each tube being in a single plane, the portion of the shell entered by the ends of the tubes having steps normal to the axes of the ends of the tubes.

7. In a water tube boiler an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending across the flue, with the greater portion of each of the tubes in each row in a plane perpendicular to the plane of the axes of the drums and inclined toward the furnace end of the flue, the distance between the outer tubes in each row being greater than the diameter of one of said drums, the axis of each end of each tube being normal to that portion of the shell of the drum which the end enters and each tube having no more than two bends, and the points of intersection of the axes of the ends of the tubes of a row with the axes of the drum being spaced apart along the drum axis.

8. In a water tube boiler, an upper and a lower cylindrical drum, with their axes horizontal and parallel, a furnace, a flue arranged to conduct the hot gases from the furnace between and longitudinally of the drum, a plurality of water tubes in the path of the gases and connecting the upper and lower drums, the tubes being arranged in rows extending across the flue, with the greater portion of each of the tubes in each row in a plane perpendicular to the plane of the axes of the drums and inclined toward the furnace end of the flue, the distance between the outer tubes in each row being greater than the diameter of one of said drums, the axis of each end of each tube being normal to that portion of the shell of the drum which the end enters and each tube having no more than two bends, and the points of intersection of the axes of the ends of the tubes of a row with the axes of the drum being spaced apart along the drum axis.

the ends of the tubes of a row with the axis of the drum being spaced apart along the drum axis, such intersections occurring along said axis in the order of the corresponding tubes from the outermost to the middle of the row.

9. In a water-tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the greater portion of each tube being inclined to the horizontal in a direction parallel to the plane of the axes of the drums, such greater portion of some of said tubes being outside the projected area of at least one of said drums, and each tube being bent 20 in a single plane, the portion of the shell of the drum which the end of a tube enters comprising a step normal to the axis of the end of the tube and the external face of each such step being partially below and partially 25 above the normal external surface of the drum shell.

10. In a water tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending 30 across the flue, with the greater portion of each of the tubes in each row in a plane perpendicular to the plane of the axes of the drums and inclined toward the furnace end of the flue, the axis of each end of each tube being normal to that portion of the shell of the drum which the end enters and each tube having no more than two bends, and the points of 35 intersection of the axes of the ends of the tubes of a row with the axis of the drum being spaced apart along the drum axis.

11. In a water tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending 40 across the flue, with the greater portion of each of the tubes in each row in a plane perpendicular to the plane of the axes of the drums and inclined toward the furnace end of the flue, the axis of each end of each tube being normal to that portion of the shell of the drum which the end enters and each tube having no more than two bends, and the points of 45 intersection of the axes of the ends of the tubes of a row with the axis of the drum being spaced apart along the drum axis, such intersections occurring along said axis in the

order of the corresponding tubes from the outermost to the middle of the row.

12. In a water tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending 50 across the flue, with the greater portion of each of the tubes in each row in a plane perpendicular to the plane of the axes of the drums and inclined toward the furnace end of the flue, the axis of each end of each tube being normal to that portion of the shell of the drum which the end enters and each tube having no more than two bends, and the ends of each tube being disposed substantially radially with respect to said drums.

13. In a water tube boiler, an upper and a lower cylindrical drum, with their axes horizontal and parallel, a furnace, a flue arranged to conduct the hot gases from the furnace between and longitudinally of the drums, a plurality of water tubes in the path of the gases and connecting the upper and lower drums, the tubes being arranged in rows extending 55 across the flue, with the greater portion of each of the tubes in each row in a plane perpendicular to the plane of the axes of the drums and inclined toward the furnace end of the flue, the axis of each end of each tube being normal to that portion of the shell of the drum which the end enters and each tube having no more than two bends, the ends of each tube being disposed substantially radially with respect to said drums, and being spaced a part lengthwise of said drums.

14. In a water tube boiler, an upper and a lower cylindrical drum, with their axes horizontal and parallel, a furnace, a flue arranged to conduct the hot gases from the furnace between and longitudinally of the drums, and a plurality of water tubes in the path of the 60 gases and connecting the upper and lower drums, the tubes being arranged in rows extending across the flue and having their ends curved where they enter the drums, the center lines of said tubes which come in a given row, including the curved ends, falling in a plane perpendicular to the plane of the axes of the drums and inclined toward the furnace end of the flue.

ISAAC HARTER. 120
